CLAIM

The ornamental design for a tobacco aerosolization device, as shown and described.

DESCRIPTION

FIG. 1 is a front perspective view of a first embodiment of the tobacco aerosolization device.

FIG. 2 is a front elevation view of the first embodiment of the tobacco aerosolization device.

FIG. 3 is a rear elevation view of the first embodiment of the tobacco aerosolization device.

FIG. 4 is a left side elevation view of the first embodiment of the tobacco aerosolization device.

FIG. 5 is a right side elevation view of the first embodiment of the tobacco aerosolization device.

FIG. 6 is a top plan view of the first embodiment of the tobacco aerosolization device.

FIG. 7 is a bottom plan view of the first embodiment of the tobacco aerosolization device.

FIG. 8 is a front perspective view of the second embodiment of the tobacco aerosolization device.

FIG. 9 is a front elevation view of the second embodiment of the tobacco aerosolization device.

FIG. 10 is a rear elevation view of the second embodiment of the tobacco aerosolization device.

FIG. 11 is a left side elevation view of the second embodiment of the tobacco aerosolization device.

FIG. 12 is a right side elevation view of the second embodiment of the tobacco aerosolization device.

FIG. 13 is a top plan view of the second embodiment of the tobacco aerosolization device; and,

FIG. 14 is a bottom plan view of the second embodiment of the tobacco aerosolization device.

The broken lines shown in the drawings are for the purpose of illustrating portions of the tobacco aerosolization device
